(57) **CLAIM**

The ornamental design for a device for spreading substances having a paste like consistency, as shown.

DESCRIPTION

FIG. 1 is a perspective view of a device for spreading substances having a paste like consistency, showing my new design;

FIG. 2 is a perspective view thereof;

FIG. 3 is a bottom view thereof;

FIG. 4 is a top view thereof;

FIG. 5 is a front view thereof;

FIG. 6 is a rear view thereof; and,

FIG. 7 is a side view thereof.
